APPARATUS FOR FORMING FABRIC STRUCTURES

Archworth Martin, Pittsburgh, Pa.

Application March 8, 1938, Serial No. 194,609

5 Claims. (Cl. 1-2)

My invention relates to apparatus for making plaster-ground fabric structures which comprise plaster-reinforcing mesh, to the rear side of which is secured a backing sheet or form sheet, 5 the fabric structure being placed upon studding or other framework with the mesh outwardly and plaster or cement then applied against the same in the forming of walls, floors, ceilings, etc.

For convenience of handling and installation, 10 it has been common practice to assemble the backing sheet and the reinforcement mesh in unitary relation at the factory. The methods heretofore employed in assembling the backing sheet and the mesh have been somewhat expensive, 15 owing to the fact that such operation has usually been performed either by the manual insertion of wire clips at various spaced points, to tie the backing sheet to the mesh, or by intermittently-operable mechanical means. In the latter case, 20 the backing sheet and the mesh are periodically advanced past a given point, and at each pause lacing wires or the like are threaded through the structure, each wire lying partly in front of the wire mesh and partly behind the paper. Not 25 only are such operations tedious and expensive, but in many instances holes of objectionable size are made in the backing sheet during insertion of the sheet-retaining or tie elements.

One object of my invention is to provide an 30 apparatus whereby reinforcement mesh and backing sheets of any length can be advanced continuously and the sheet automatically attached to the mesh during said advancing movement.

Another object of my invention is to provide an 35 improved means for attaching backing sheets to reinforcement mesh, without tearing or cutting of the sheets to an objectionable degree.

The apparatus of this application is a modification of the apparatus disclosed in my co-pending 40 application Serial No. 188,283, filed February 2, 1938, which is directed to a method of attaching backing sheets to reinforcement mesh during continuous traveling movement thereof.

Figure 1 is a side view of the machine, partly 45 in section; Fig. 2 is a sectional plan view thereof, taken on the line II-II of Fig. 1; Fig. 3 is an enlarged view taken on the line III-III of Fig. 2, showing the cutters for cutting certain of the stay wires from which tangs are formed; Fig. 4 50 is an enlarged view taken on the line IV-IV of Fig. 2 and showing the dies for bending the tangs; Fig. 5 is an enlarged view taken on the line V-V of Fig. 1; Fig. 6 is a plan view of the structure of Fig. 5; Fig. 7 is a view taken on the 55 line VII-VII of Fig. 6; Figs. 8 and 9 are enlarged

fragmentary views of portions of the apparatus of Fig. 1, and showing the preliminary and final bending of the tangs; Fig. 10 is an enlarged view of a portion of the tie feeding apparatus of Fig. 1, and Fig. 11 is a plan view thereof. 5

The wire fabric or mesh to which a backing sheet is to be applied is composed of a suitable number of laterally-spaced strand wires 2, having welded thereto cross wires or stay wires 3. The backing sheet is represented by the numeral 10 4 and is drawn from a supply roll 5 in a manner 15 to be hereinafter described. The wire mesh can also be drawn from a supply roll, not shown, or directly from the machine on which it is fabricated. 15

The mesh and the backing sheet 4 are advanced 20 between a carrier 6 and a tie bar conveyor 7, both the carrier and the conveyor being continuously driven in synchronism and exerting a pull on the stay wires 3. The apparatus is driven 25 by a motor 8 which, through a worm gear reducing unit 9, drives a pinion 10 that meshes with a gear wheel 11 secured to a shaft 12 journaled in the framework of the machine. The gear wheel 11 drives a gear wheel 13 which is mounted on a 30 transverse shaft 14. The shaft 14, at its other end, carries a pinion 15 that meshes with a gear wheel 16. The gear wheel 16 is mounted on a shaft 17 which carries sprockets 18 whose teeth 35 mesh with the links of carrier chains 19. The carrier chains also pass around sprockets 20 that are mounted on a transverse shaft 21. Gear wheel 16 meshes with a gear wheel 22 that is mounted on a shaft 23. The shaft 23 carries sprockets 24 that mesh with carrier chains 25 35 that also pass around sprockets 26. 35

As the mesh is advanced by the carrier and conveyor, it is drawn past a cutting and bending station A where alternate stay wires 3 are cut and the cut ends bent perpendicularly with respect to the plane of the mesh, to form tangs 27 40 which are to be projected through the backing sheet 4. The cutting and bending apparatus includes a slide bar 28 that extends crosswise of the fabric and is moved in vertical guideways formed in the framework of the machine. A cross bar 29 is rigidly mounted on the framework in a position above the movable bar 28. The bars 28 and 29 carry a series of cutting knives or dies 30 and 31, as shown more clearly in Fig. 3, whereby a stay wire is cut at a plurality of 50 points simultaneously upon upward movement of the bar 28. The bars 28 and 29 also carry bending dies 32 and 33 respectively (Fig. 4). The bar 28 is reciprocated vertically by cams 34 se- 55

cured to a shaft 35 which is mounted in the framework of the machine. The bar 28 at each end carries a roller 36 which is engaged by the cams 34, the bar 28 being yieldably urged downwardly by springs 37. The shaft 35 carries a bevel gear wheel 38 which meshes with a gear wheel 39 that is mounted on a shaft 40. The shaft 40 has a bevel gear connection at 41 with the shaft 12.

10 The bar 28 is reciprocated in timed relation to movement of the carrier and the conveyor, and upon each upward movement thereof a stay wire will be cut at a plurality of points through co-operation of the knives 30 and 31. Simultaneously, the severed ends of a previously-cut wire will be bent into perpendicular relation through movement of the bending dies 32 toward the dies 33. As shown in the drawings, only alternate stay wires are thus cut and bent. Also, the stays 20 are cut only between alternate pairs of strand wires.

The backing sheet 4 is drawn past tensioning rollers 43 and beneath a presser roller 44 which is preferably grooved to permit the tangs 27 to pass the same. A back-up or supporting roller 45 is idly journaled in the machine frame. As the tangs approach the rollers 43 and 45, they are pushed through the sheet 4 and the sheet is pressed flatly against the mesh by the roller 44.

30 Tie wires 46 are deposited one-by-one upon the top of the sheet and against the rear sides of each transverse row of tangs 27, by the conveyor 7. The chains 25 carry conveyor bars 47 which are notched or grooved in their outer forward corners 35 at 48, to provide seats thereon for the tie wires 46.

The tie wires 46 are severed and suitably deposited upon supporting ways 49 (Fig. 1), where they are advanced into a chute 50 by the frictional drag of a conveyor 51, the conveyor 51 thereby exerting a constant advancing force on the ties. A gate 52 is slidably supported beneath the chute 50 and is yieldably projected forwardly by a spring 53. The gate 52 has forwardly-projecting fingers or nose portions 54 grooved at their upper sides to receive the foremost tie 46, when it is pressed rearwardly to the position shown in Fig. 10. Normally, however, the gate 52 is in forwardly-projected position as shown in Fig. 1. At this last-named position, the fingers 54 support a tie wire in position to be engaged in the recess 48 of a conveyor bar 47. The conveyor bars 47 are magnetized so that the wires will be retained in position on the conveyor when they are moved from the fingers 54. The bars 47 are slotted at 55 their forward edges, as indicated at 55, in order to permit bending back of the tangs over the tie wires, as shown more clearly in Figs. 5 to 9, and as will be hereinafter described. This slotting of the bars also provides a cam surface 56 (Fig. 10) that

60 engages the nose portions 54 of the gate immediately after the bar has picked up a tie wire, and forces the gate rearwardly in position to receive another tie wire. After the bar 47 passes the gate, the gate will be projected forwardly by 65 its spring 53 to bring another tie wire in position to be picked up by the succeeding bar 47.

The spacing of the bars is such that each tie wire will be brought into position behind a transverse row of tangs 27, as shown in Fig. 1. As the 70 mesh and the tie wires are advanced, the tangs 27 will be bent to the position shown in Fig. 8 by toothed wheels 60 that preferably are driven at very high speed in a direction to bend the tangs backwardly over the tie wires. The wheels 60 are 75 secured to a shaft 61 which carries a pulley that

is driven by a belt 62 from a pulley 63 on a shaft 64. The shaft 64 has bevel gear connection at 65 with a shaft 66 which is provided with a pulley driven by a belt 67, which in turn is driven by a pulley 68 that is mounted on the shaft of the motor 8. The forward thrust of the conveyor 7 prevents displacement of the tie bars during this bending operation.

When the partially bent tangs have passed the bending wheels 60, they are brought into engagement with presser wheels 70 which have bosses 71 that engage the partially bent tangs to bend them into closely-embracing engagement with the tie bars, as shown in Fig. 9. The wheels 70 are mounted on a shaft 72 which is journaled in the framework of the machine and carries a pair of sprocket wheels 73 whose teeth mesh with the chain links 25 of the conveyor 7, the rotation of the wheels 70 being thereby effected. Bars 75 are rigidly mounted in the framework of the machine 20 and support the flights of the carrier 6 against downward deflection under pressure of the wheels 60 and 70.

In order to permit of faster traveling movement of the mesh and the paper and hence 25 increased rate of output, a plurality of sets of tang-forming and bending elements may be provided instead of the single set shown at the station A. Each set of tang-cutting and bending dies would, therefore, operate upon stay wires 30 which were not cut and bent by the other dies. This plural arrangement of tang-forming elements is particularly desirable where lightweight wall fabric, with close spacing of the stay wires, is being produced. In producing floor fabric or concrete reinforcement where the wires are quite heavy and spaced much greater distances apart, a single set of cutting and bending dies will be sufficient.

From the foregoing it will be seen that the mesh 40 and the sheet are advanced by the carrier 6 and the conveyor 7 and that simultaneously with such movement the tang-forming dies are operated and the backing sheet 4 drawn from the roll and pressed against the mesh. The conveyor 7 brings 45 the tie wires 46 into position against the rear side of the tangs and such tangs are bent and clenched by the members 60 and 70 while the fabric is being advanced through the machine.

It will be seen that as the mesh and the paper 50 are advanced by the carrier and the conveyor, all of the operations above referred to are automatically effected. When the assembled paper and mesh leave the machine, they can be cut either into sections or taken up on a roll.

I claim as my invention:

1. Apparatus for attaching a backing sheet to reinforcement mesh, comprising means for shearing portions of the mesh at certain points thereof and bending the sheared portions upwardly to 60 form rows of tang elements which extend transversely of the mesh, means for bringing the mesh into position against one face of a sheet, with the tangs projecting through the sheet, means for moving tie strips against the other face of the 65 sheet, each in proximity to a row of tangs, and means operable to bend the tangs over the tie strips.

2. Apparatus for attaching a backing sheet to reinforcement mesh, comprising means for bringing a sheet and a tanged mesh into superposed relation, with the tangs projecting through the sheet, a carrier engageable with the mesh to effect advancing movement thereof, a conveyor for moving tie strips into crosswise position against 70 75

the exposed face of the sheet and against the rear sides of the tangs, and a bending element operable in a direction opposite to the movement of the carrier, for bending the tangs backwardly over the tie strips.

- 5 3. Apparatus for attaching a backing sheet to reinforcement mesh, comprising means for bringing a sheet and a tanged mesh into superposed relation, with the tangs projecting through the 10 mesh, a carrier engageable with the mesh to effect advancing movement thereof, a conveyor for moving tie strips into position against the exposed face of the sheet and against the rear sides of the tangs, a bending element operable in a direction 15 opposite to the movement of the carrier for bending the tangs backwardly over the tie strips, and a second bending element movable with the carrier, for clenching the tangs into embracing engagement with the tie strips.

- 20 4. Apparatus for attaching a backing sheet to

reinforcement mesh, comprising means for imparting advancing movement to the sheet and a tanged mesh, from relatively angular paths to parallel planes, and for simultaneously forcing the tangs through the sheet, means for placing tie strips against the exposed face of the sheet, and means operable in timed relation to said advancing movement, for bending the tangs over the tie strips.

- 5 5. Apparatus for attaching a backing sheet to reinforcement mesh, comprising means for imparting advancing movement to the sheet and a tanged mesh, from relatively angular paths to parallel planes, and for simultaneously forcing the tangs through the sheet, means for placing tie strips crosswise against the exposed face of the sheet, and means operable in timed relation to said advancing movement, for bending the tangs over the tie strips.

10 ARCHWORTH MARTIN. 15 20
